US00D975077S

(12) **United States Design Patent** (10) **Patent No.:** **US D975,077 S**
(45) **Date of Patent:** **** Jan. 10, 2023**

(54) **PHONE CASE**

(71) Applicant: **Shenzhen Gumi Technology Co., LTD.**, Shenzhen (CN)

(72) Inventor: **Zhaojian Wei**, Shenzhen (CN)

(73) Assignee: **Shenzhen Gumi Technology Co., LTD.**, Shenzhen (CN)

(**) Term: **15 Years**

(21) Appl. No.: **29/797,517**

(22) Filed: **Jun. 30, 2021**

(51) LOC (14) Cl. **14-03**

(52) U.S. Cl.

USPC **D14/250**

Primary Examiner — Carla J Wright

(57) **CLAIM**

The ornamental design for a phone case, as shown and described.

DESCRIPTION

FIG. 1 is a front elevation view of a phone case showing my new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof; and,

FIG. 7 is a back, right-side, and top perspective view thereof. The broken lines form no part of the claimed design and depict portions of the phone case that form no part of the claimed design. The interior of the phone case that is shown in FIG. 1 forms no part of the claimed design.

1 Claim, 7 Drawing Sheets
